(57) **CLAIM**

The ornamental design for a female pelvic heating pad, as shown and described.

DESCRIPTION

FIG. 1 is a front view of a female pelvic heating pad showing my new design;

FIG. 2 is a rear view thereof;

FIG. 3 is a left side view thereof;

FIG. 4 is a right side view thereof;

FIG. 5 is a top view thereof; and,

FIG. 6 is a bottom view thereof.

In FIG. 1, the portion of the female pelvic heating pad shown in broken lines form no part of the claimed design.
